UNITED STATES PATENT OFFICE

ARISTEDE A. THEODOPOULOS, OF NEW YORK, N. Y.

SAFETY RAZOR

Application filed November 26, 1927. Serial No. 235,762.

This invention relates generally to razors and has more particular reference to the so called safety razor.

The invention has for an object the provision of a safety razor of simple desirable construction, which is efficient in operation, and which can be manufactured and sold at a reasonable cost.

The invention consists in forming a top clamp member with elongated projections on its underside, and threadedly connecting a handle therewith, a razor blade and a safety member being clamped between the top clamp member and the handle. The razor blade and the safety member are formed with elongated slots engaging the said elongated projections. The edges of the safety member are formed with very wide openings, and the safety razor is designed to be flat and not curved when clamped. An auxiliary safety member is slidably and adjustably arranged on the safety member so that the said wide openings may be adjusted.

For further comprehension of the invention and of the objects and advantages thereof, reference will be had to the following description and accompanying drawings, and to the appended claims in which the various novel features of the invention are more particularly set forth.

Referring to the accompanying drawing, forming a material part of this disclosure:

Fig. 1 is a perspective view of a device constructed according to the invention.

Fig. 2 is a side view of the top clamp member, used in the invention device.

Fig. 3 is a bottom view of the clamp member shown in Fig. 2.

Fig. 4 is a plan view of a razor blade used in this invention.

Fig. 5 is a plan view of a safety member used in this invention.

Fig. 6 is a side view of a handle used in this invention.

Fig. 7 is a fragmentary transverse vertical sectional view, looking in the direction of arrows 7-7 of Fig. 1.

The reference numeral 10 indicates generally a top clamp member provided on its underside with a pair of elongated projections

11 and a central threaded aperture 12. A handle 14 having a knurled design thereon, is formed with a threaded reduced end 15, forming a shoulder 16, the threaded end 15 being engageable in the threaded aperture 12. 55

A razor blade 17 is formed with a pair of elongated slots 18 engageable with the projections 11 and with an aperture 19 aligned with aperture 12 when the projections 11 engage the slots. 60

A safety member 20 is formed with elongated slots 21 engageable with projections 11 and a central aperture 22 aligned with apertures 19 and 12 when the parts are in place. The edges of the safety member are formed 65 with very wide openings 23. The blade 17 is placed beneath the top clamp member 10 and safety member 20 beneath the blade 17, and the part 15 of the handle is passed through the apertures 22 and 19 and engaged 70 in 12, the shoulder 16 acting to hold the parts tightly in place.

The safety member 20 is provided with an auxiliary safety member 20^a slidably connected by means of dove-tailed connection 31. A set screw 32 threadedly passes through member 20^a and abuts member 20 to lock auxiliary member 20^a in adjusted positions. The size of the openings 23 may be adjusted 75 by adjusting the position of the auxiliary member 20^a and this adjustment changes the amount of cut hair and soap which enters and passes through openings 23.

It is thought that the shaving operation of the invention is clear from the above disclosure. 85

While I have described my invention with some degree of particularity, I realize that in practice various alterations therein may be made. I therefore reserve the right and privilege of changing the details or otherwise altering the arrangement of the correlated parts without departing from the spirit or the scope of the appended claims. 90

Having thus described my invention, what I claim as new and desire to secure by United States Letters Patent is:

1. In a safety razor, a safety member with wide openings, for clamping a razor blade against a top member, an auxiliary safety 95

member slidably mounted on the said safety member, and a set screw threadedly passed thru the auxiliary safety member and abutting the said safety member so that the operative size of the wide openings of the safety member may be adjusted.

2. In a safety razor, a safety member with wide openings, for clamping a razor blade against a top member, an auxiliary safety member slidably mounted on the said safety member by means of a dove-tailed connection, and a set screw threadedly passed thru the auxiliary safety member and abutting the said safety member so that the operative size of the wide openings of the safety member may be adjusted.

3. In a safety razor, a safety member with wide openings, for clamping a razor blade against a top member, an auxiliary safety member slidably mounted on the said safety member, and a means for holding the auxiliary safety member in fixed positions relative to the said safety member so that the operative size of the wide openings of the safety member may be adjusted.

In testimony whereof I have affixed my signature.

ARISTEDE A. THEODOROPULOS.
